By Atty.

UNITED STATES PATENT OFFICE.

THOMAS NELSON EVENS, OF LONDON, ENGLAND.

INTERCHANGEABLE LETTER.

1,405,991.

Specification of Letters Patent. Patented Feb. 7, 1922.

Application filed August 4, 1920. Serial No. 401,210.

(GRANTED UNDER THE PROVISIONS OF THE ACT OF MARCH 3, 1921, 41 STAT. L., 1313.)

To all whom it may concern:

Be it known that I, THOMAS NELSON EVENS, a citizen of the United Kingdom of Great Britain and Ireland, and resident of 5 4 Eagle Street, London, W. C. I., England, have invented certain new and useful Improvements in and Relating to Interchangeable Letters, (for which I filed an application in England July 8th, 1916, No. 104812,) 10 of which the following is a specification, such as will enable others skilled in the art to which it appertains to make and use the same.

This invention relates to advertising and 15 the like notices or display boards of the kind in which removable letters, figures and signs are slidably mounted upon a back or base which is furnished with grooves or passages, adapted to take projections on the back of 20 the letters or equivalents, for the purpose of supporting them in alignment on the said back or base.

My invention applies particularly to that 25 type of device in which the letters or equivalents are attached to spacing bars adapted to slide in the said grooves and the particular feature of the invention is that whilst the spacing bar may be of any suitable kind the support from it to the letter, instead of 30 being wide like the bar and visible from the front is narrow, so as to be practically invisible, being covered by the width of the letter, thereby greatly enhancing the appearance of the appliance, and in addition 35 to this, the said narrow support is of such length as will hold the letter or figure away from the board.

A simple form of my invention is shown 40 with some modifications in the accompanying drawings in which:—

Fig. 1. shows a base or back having front formed of wood or other strips *a* between which are narrow slits *b* enlarged into tube-like openings *c*. This front is supported by 45 a piece of solid wood or other suitable material *d*. This figure shows one of the forms of letters *f* used and its means of support. This support comprises a flat strip *g* attached to bar *h*. The bar *h* is a close fit in 50 the tube-like opening *c* whilst the strip *g*

pretty closely fits the slot *b* but is distinctly longer than the depth of the slot so that it holds the letter away from the face of the board or base.

Fig. 2. illustrates another form of back or 55 base made of say thin wood or card strips *i*, *j*, and *k*.

Figs. 3. and 4 show a letter suitable for use on the back or base shown in Fig. 2.

Like reference letters are used in Figs. 60 3 and 4, for substantially like parts as those used in Fig. 1.

Fig. 5, shows a letter *f* with spacing bar and strip formed from one piece of sheet metal. In all these examples the supporting 65 strips are attached to the letters about midway between the upper and lower edges. Spacing bars without letters and of substantially known forms such as shown in Figs. 6. and 7 may be used if desired for forming 70 margins and other spacing purposes. Any suitable form of letter, figure, words signs or equivalents may be employed. The end of the openings *c* may be closed by plugs or equivalents. 75

What I claim and desire to secure by Letters Patent is:—

1. In combination, a base formed with parallel passages having slots extending from said passages and through one surface 80 of the base, formed characters having bars of a size to fit in said passages, and strips connecting said bars and characters, said bars being of greater length than the width of the character to form spaces between the 85 characters when assembled, said strips engaging in the slots and being wholly concealed by a portion of the character and being of a length exceeding the depth of the slot with which it cooperates, whereby to 90 hold the characters in spaced relation with reference to the face of the base.

2. In combination, a base formed with parallel passages having slots extending from said passages and through one surface 95 of the base, formed characters having longitudinal resilient bars to engage the surfaces of the passages and being of greater length than the width of the character to form spaces between the characters when assem- 100

bled, and strips connecting the characters and the bars and engaging in the slots, said strips being of a length exceeding the depth of the slot with which they cooperate, whereby to hold the characters in spaced relation with reference to the face of the base.

In witness whereof I have hereunto set my hand in presence of two witnesses.

THOMAS NELSON EVENS.

Witnesses:

EWART FRANK MATHIAS,
RICHARD JOHN LAKE.
